CLAIM

The ornamental design for a stackable pocket planter, substantially as shown and described.

DESCRIPTION

FIG. 1 is a perspective view of a stackable flower pot showing my new design;

FIG. 2 is a reduced front elevational view thereof;

FIG. 3 is a reduced top plan view thereof;

FIG. 4 is a reduced bottom plan view thereof.

FIG. 2
